(57) **CLAIM**

The ornamental design for a clothing garment as shown and described.

DESCRIPTION

This application is related to co-filed application for design patent, entitled Clothing Garment, invented by the same inventor and filed on Jun. 4, 2024, assigned U.S. Design application Ser. No. 29/945,573.

FIG. 1 is a perspective view of a clothing garment showing my new design;

FIG. 2 is a left side view thereof;

FIG. 3 is a right side view thereof;

FIG. 4 is a top view thereof;

FIG. 5 is a bottom view thereof;

FIG. 6 is a front view thereof; and,

FIG. 7 is a rear view thereof.

The broken lines illustrate portions of the clothing garment that do not form a part of the claimed design.

The invention includes mirror images of the clothing garment shown in the Figures.

1 Claim, 7 Drawing Sheets
